cago, Ill., a corporation of Delaware

Application January 14, 1937, Serial No. 120,507

22 Claims. (Cl. 179—27)

The present invention relates in general to improvements in telephone systems, but is particularly concerned with means for handling long distance or toll calls in connection with an automatic telephone system.

When a toll call is received at an automatic exchange, it usually comes in on a manual switchboard. An operator thereat, upon learning the number of the wanted subscriber, sets up the connection by means of a suitable cord circuit and the automatic switches in the usual manner.

It is desirable that a toll call be given preference over a local call so that the toll trunk lines between cities will not be tied up for a single call any longer than is absolutely necessary. The operator that receives a toll call frequently finds that the wanted subscriber's line is busy. For instance, if two automatic subscribers are talking over a local connection and either of these subscribers is wanted for a toll connection, it is desirable that the operator be able to inform the desired subscriber that he is wanted for a toll call. In order to accomplish this purpose, a new and improved connector switch has been provided by means of which the operator can establish a connection with a busy line and inform the wanted subscriber thereon of the waiting toll call.

The object of the invention is to provide a toll offering connector switch that is accessible both to local subscribers and to the toll operator in order that connections may be extended to wanted subscribers in an automatic system. Since all the connector switches in the telephone system are capable of seizing either idle lines or busy lines, special arrangements must be provided whereby the seizure of a switch by a regular subscriber prevents that switch from cutting in on a busy line; and whereby the seizure of a switch by the toll operator permits the operator to control that switch, when a busy line is encountered, to cut in on the busy line and offer the toll connection to the wanted subscriber. Heretofore, the operator has been provided with a key to ground the conductors of the trunk line to unbalance a differentially wound relay in the connector. This caused the operation of the differential relay and permitted the connector to cut in on a busy line. With this type of toll offering connector, the regular local subscribers soon found out that they could control the connector to cut in on busy lines by merely grounding one of their line conductors momentarily and thus eavesdrop on private conversations. In fact, a discharged telephone employee has sold an apparatus that would perform this operation, to regular subscribers in a telephone system.

In this present invention, toll offering by the

operator is controlled by the momentary application of positive booster battery to the conductors of the trunk line to control the connector to cut in on a busy line. This practically eliminates the possibility of a local subscriber controlling a connector to cut in on a busy line, since the connector will only cut in on a busy line when positive booster battery is applied to the trunk conductors.

Another object of the invention is to provide a trunk repeater over which connections are extended to subscribers in a distant automatic exchange. The trunk repeaters are accessible to local automatic subscribers and to the toll operator to extend connections thereover. Furthermore, the operator can control the trunk repeater to connect positive booster battery to the trunk line conductors and thereby control the connectors in the distant automatic exchange to cut in on busy lines.

The foregoing objects, together with others not specifically pointed out, will be described hereinafter with reference to the accompanying drawings comprising Figs. 1, 2, and 3. The drawings show by means of the usual circuit diagram sufficient of the apparatus involved to permit the same to be readily understood.

Fig. 1 shows the calling end of a toll operator's dialling cord O, terminating in a plug P, and equipped with a dialling key K. The dial CD may be associated with the cord circuit O by operating the key K to the right. The cord circuit O may be of any suitable type and is therefore not shown in full; only those elements which concern the invention are shown. The line switch LS, accessible to the operator at the jack J, is one of a plurality of line switches accessible to the operator over a like number of jacks, such as jack J. The regular telephone subscribers' lines also terminate in line switches and are accessible in the banks of the connectors. The line switch LS may be of the same construction as the line switch LS—1 shown in Fig. 2, which is of the well-known rotary type having no normal position and moves its wipers in one direction only. The line switch LS, together with all other line switches in the system, have access to selector switches, such as selector switch S. The selector S is of the well-known vertical and rotary type of Strowger switch and has access to outgoing trunk repeaters, such as outgoing trunk repeater OTR, and to connector switches, such as connector switch C.

In Fig. 2 there is shown a connector switch C, which is of the well-known vertical and rotary type of Strowger switch, that has been modified by additional relays, the function of which is part of this invention and will be described in detail subsequently in connection with the operation of the connector switch shown. The con-

5 nector switch C has access to automatic subscribers' lines, such as the line of substation A. The substation A is of the type usually found in all automatic telephone systems, and is shown 10 with its line conductors terminating at the exchange in the individual line switch LS-1, which has access to selector switches, such as selector switch S shown in Fig. 1. The line switch LS-1 is a standard rotary line switch of the type disclosed in Patent No. 1,693,037, granted to John Erickson, November 27, 1928. This switch is of the step-by-step type in which the wipers move in a forward direction only, and in which the wipers are advanced when the stepping magnet 15 retracts its armature rather than when it attracts its armature.

In Fig. 3 is shown an outgoing trunk repeater OTR, which is one of a plurality of trunk repeaters accessible, for example, from the "O" 20 level of the selector switch, such as selector switch S, and is used to extend calls over the trunk line comprising conductors 30 and 31 to a distant automatic exchange.

Throughout the drawings numerous types of 25 relays, well known in the automatic telephone art, are shown. Slow-to-operate relays are shown having a solid black upper section. Slow-to-release relays are shown either with a cross-hatched lower section or with double lines representing a copper sleeve on the cores of the relays. The shunt field relay in Fig. 3, is shown by representing the two windings of the relay on 30 separate cores included in a shunted magnet circuit. A number of three-pole relays of the type covered by Pye Patent No. 1,673,884, issued June 19, 1928, are also employed and are shown with their cores equipped with a bar magnetically separating the two windings of the relays. This type of relay only operates when the circuit 35 through both its windings assist each other when they are energized, or when the energizing circuit is completed through its upper or operating winding alone, and will not operate when the energizing circuits through both its windings 40 oppose each other.

In order to make the invention clear, it is believed advisable to describe the manner of operation by explaining how a connection is established between two local automatic telephone 50 subscribers and then by explaining the operation when the toll operator extends a connection to a busy line.

For this purpose, it will be assumed that a local 55 automatic telephone subscriber, whose substation equipment is similar to that of the subscriber at substation A, has removed his receiver from the switch-hook and has dialled the directory number of the subscriber at substation A. Responsive to the removal of the receiver at the 60 calling subscriber's substation, a line switch similar to line switch LS-1 shown in Fig. 2, operates in the usual manner and extends the connection to an idle selector switch, such as selector S, over the trunk conductor 10, 11 and 12. The calling subscriber receives the usual dial tone signal 65 to indicate that the selector is in a position to receive the first digit of the called number. Responsive to the dialling of the first digit of the called number, selector S operates to raise its wipers 13-15, inclusive, opposite the level of the bank contacts corresponding to the digit dialled, and then the wipers are automatically rotated to 70 select an idle trunk line accessible in that level.

It will be assumed that the first idle line 75 encountered by the wipers 13-15, inclusive, is the

trunk line comprising conductors 16-18, inclusive, extending to connector C, shown in Fig. 2. When the connection is extended to connector C, line relay 203 energizes and prepares the connector for operation. The energizing circuit for line relay 203 may be traced over the following path: ground, upper winding of line relay 203, upper or operating winding of the three-pole electro-polar relay 202, normally closed contacts controlled by armature 214, conductor 18, wiper 15 of the selector S, conductor 12, over the calling subscriber's line switch and subscriber's line and return, conductor 10, through the selector S, wiper 13 of the selector, conductor 16, normally closed contacts controlled by armature 215, lower or polarizing winding of the three-pole electro-polar relay 202, lower winding of line relay 203, to battery. Line relay 203 operates and completes an obvious energizing circuit for slow-to-release relay 204 at armature 219. Release relay 204, upon operating, at armature 216 grounds the release conductor 17 to maintain the preceding switches operated, opens a point in the circuit for the release magnet 213 at armature 218 and its back contact, and at its front contact 25 closes a point in the operating circuit of vertical series relay 205 and the vertical magnet 211. The closing of the contacts at armature 217 prepares a holding circuit for ring-cut-off relay 206 and switching relay 210 that will be explained subsequently.

The connector switch C is now in readiness to receive the second series of impulses corresponding in number to the second digit of the called number. Responsive to the second operation of the calling device at the calling subscriber's station, the circuit of line relay 203 is interrupted a number of times. Attention is called to the fact that the flux generated by the current flow through the upper winding of the three-pole electro-polar relay 202 is in opposition to the flux generated by the current flow through the lower winding, therefore, the relay does not operate. The first time the line relay 203 falls back, a circuit is completed from ground, armature 219 and its resting contacts, armature 218 and its front contact, contacts 220 of the off-normal springs ON, winding of vertical series relay 205, winding of the vertical magnet 211, to battery. Vertical magnet 211 operates over this circuit and 40 raises the shaft and wipers of the switch in the well-known manner, one step. Vertical series relay 205 operates in series with the vertical magnet 211. The contacts 220 of the off-normal springs ON are open and contacts 221 are closed 45 in response to the raising of the shaft and wipers of the switch. Each succeeding time the circuit of line relay 203 is interrupted, a circuit is completed from ground, armature 219 and its resting contacts, armature 218 and its front contact, contacts 221 of the off-normal springs ON, armature 222 and its front contact, winding of the vertical series relay 205, winding of the vertical magnet 211, to battery. Due to their slow-release characteristics, relay 204 and relay 205 50 remain energized throughout the series of impulses. Vertical magnet 211 operates in the well-known manner to raise the wipers 223-225, inclusive, opposite the level of bank contacts corresponding to the number of impulses transmitted by the calling subscriber. At the end of the vertical movement, vertical series relay 205 falls back and by closing the resting contacts of armature 222 prepares the circuit for operating 55 rotary magnet 212 in parallel with relay 209. 60

Responsive to the dialling of the last digit by the calling subscriber, the rotary magnet 212 and relay 209 are operated over the following circuit: ground, armature 219 and its resting contact, 5 armature 218 and its front contact, contacts 221 of the off-normal springs ON, armature 222 and its resting contact, armature 226 and its resting contact, over one path including the winding of relay 209, to battery, and over the other path including armature 228 and its resting contact, winding of the rotary magnet 212, to battery. Each time the line relay 203 falls back, in response to the impulses transmitted from the calling subscriber's dial, the rotary magnet 212 operates 10 in the well-known manner to advance the wipers 223-225, inclusive, into engagement with the contacts of the called line. It should be noted that at armature 229 and its resting contact, relay 209 opens a point in the operating circuit 15 of the switching relay 210 and at the front contact of this armature connects the test wiper 224 to the winding of the busy test relay 208. Relay 209 also, at its armature 227, completes a circuit around armature 226 and its resting 20 contact in order to guard against the rotary magnet circuit being interrupted by the operation of busy test relay 208 as a result of wiper 224 passing over busy test contact.

It will be assumed that the wipers 223-225, inclusive, have been rotated, in response to the dialling of the last digit, into engagement with the bank contacts to which conductors 230-232, inclusive, of substation A are connected. Relay 209, due to its slow release characteristics, remains energized a short period of time after the last impulse has been received. If the subscriber at substation A is engaged in a conversation, ground is encountered on test conductor 231, by the test wiper 224 of the connector switch C, and a circuit is accordingly completed by way of armature 229 and its front contact, armature 233 and its resting contact, winding of the busy test relay 208, to battery. Busy test relay 208 operates over this circuit and at armature 229 and its 45 front contact prepares a locking circuit for itself and at armature 242 connects the busy tone to conductor 18 to give the calling subscriber the busy signal. Relay 209 subsequently falls back and at the normally closed contact controlled by the front contact of armature 229 completes the locking circuit for busy relay 208 from ground at armature 216 of the operated release relay 204. At armature 241 and its front contact, busy test relay 208 prepares a circuit for the toll offering 50 relay 207, but since the calling subscriber has no facilities for initiating the operation of the three-pole electro-polar relay 202, the toll offering relay 207 cannot be operated at this time.

When the calling subscriber hears the busy tone transmitted back over his line, he hangs up his receiver and accordingly opens the circuit for the line relay 203. Upon falling back, line relay 203 opens the circuit of release relay 204. Relay 204 restores and at armature 216 removes ground 55 from the release trunk conductor 17 to permit the preceding switches to release. At armature 218, relay 204 completes a circuit from ground at the resting contact of armature 219, armature 218 and its resting contact, lower armature and resting contact of back-bridge relay 201, contact 245 of the operated off-normal springs ON, winding of the release magnet 213, to battery. Release magnet 213 operates, causing the shaft and wipers of the switch to restore to normal. The op-

erated busy relay 208 falls back when the holding ground is removed at armature 216.

It should be noted that when the subscriber at substation A is busy that the test wiper 224, of the connector switch C, encounters a ground potential on the bank contact to which test conductor 231 is connected. Ground is applied to conductor 231 either from the upper armature and front contact of the line relay 234 of the line switch LS-1, or from the test conductor of the selector switch to which test wiper 347 of the line switch LS-1 is connected by way of armature 236 and its front contact. Furthermore, it should be understood that the selector switch to which the line switch LS-1 is in engagement with is similar to selector S shown in Fig. 1, and that the connector switch used to complete the connection with the wanted subscriber, is similar to the connector switch C shown in Fig. 2.

Having explained the operations that take place when a local subscriber endeavors to establish a connection with a busy subscriber at station A, a description will now be given of the operation of the circuit when the wanted subscriber's line is idle. It will now be assumed that the line of the wanted subscriber at substation A is idle when the calling subscriber has operated the connector C to his line. Such being the case, when the test wiper 224, of the connector switch C, comes to rest in engagement with the test contact to which conductor 231 is connected, it will find no ground potential and the busy test relay 208 will not be energized. Instead, when the slow acting relay 209 falls back, shortly after the last impulse has been received for operating the rotary magnet 212, a circuit is closed through the lower winding of the switching relay 210 as follows: from ground by way of armature 216, armature 240 and its resting contacts, lower winding of switching relay 210, armature 229 and its resting contacts, test wiper 224, conductor 231, winding of cut-off relay 233 of the line switch LS-1, self-interrupting contacts of the operating magnet 249, winding of the operating magnet 249, to battery. When the above traced circuit is completed, the cut-off relay 233 of the line switch LS-1, is operated to clear the line of the substation A of its normal battery and ground connections in the line switch LS-1. It should be noted that relay 233 is not fully operated at this time, due to a mechanical interlocking arrangement between the armature of this relay and the armature of the line relay 234, and the wipers of the line switch LS-1 are not connected up. The switching relay 210, of the connector C, also operates over this circuit and completes a locking circuit for itself by way of its upper winding, armature 250, and ground at armature 217. In addition, armature 254 connects ground to the test wiper 224 thereby connecting a guarding potential to conductor 231 and multiples thereof, armature 228 opens the impulsive circuit of rotary magnet 212, and armature 238 opens the circuit of the busy test relay 208. At armatures 251 and 253, switching relay 210 connects interrupted generator to the called line and at armature 252 connects a ring-back tone circuit to the calling line.

The connection to the desired line has now been completed and the ringing current from the generator, INT. GEN., is intermittently transmitted out over the line to operate the ringer at substation A. The ringing circuit may be traced as follows: from interrupted generator INT. GEN., winding of ring-cut-off relay 206, armature 255,

armature 251, wiper 223, conductor 230, condenser and ringer at substation A, conductor 232, wiper 225, armature 253, armature 257, to ground. A portion of the generator current passes through 5 small capacity condenser 258, armature 252, and conductor 16, to the telephone at the calling station for transmitting the well-known ring-back tone to the calling subscriber each time the called party's bell is rung. The ringing current 10 is intermittently transmitted over this circuit until the called subscriber lifts his receiver, thereby short-circuiting the bell and condenser at his station and completing a direct current path over the above traced circuit for the lower winding of ring-cut-off relay 206. Ring-cut-off relay 15 206 operates and at armature 256 completes a locking circuit for its upper winding from ground at armature 217. At armatures 255 and 257 and their resting contacts relay 206 opens the ringing circuit and at the front contacts of these armatures it completes the talking circuit to the subscriber at substation A.

Responsive to the completion of the talking circuit, back bridge relay 201 operates over the 25 called subscriber's loop as follows: ground, lower winding of back bridge relay 201, armature 260 and its resting contact, armature 257 and its front contact, armature 252 and its front contact, wiper 225, conductor 232, over the called subscriber's line, and back over conductor 230, wiper 223, armature 251 and its front contact, armature 255 and its front contact, armature 259 and its resting contact, upper winding of back bridge relay 201, to battery. At armature 261 and its front contact, relay 201 closes another point in the circuit for grounding release trunk conductor 17 and at armature 262 completes an additional locking circuit for the ring-cut-off relay 206 and the switching relay 210. The grounding 30 of release trunk conductor 17 at armature 261 35 and armature 216, and the two locking circuits for maintaining the ring-cut-off relay 206 and switching relay 210 at armatures 262 and 217, is for the purpose of maintaining the connector in its operated position until the last party of the 40 connected subscribers hangs up his receiver. Relay 201 maintains the connector in an operated position as long as the called subscriber does not hang up his receiver and the release relay 204 maintains the connector in an operated position 45 as long as the calling subscriber has his receiver off the switch-hook. As a further result of the operation of the back bridge relay 201, the connections between the windings of the line relay 203 and trunk conductors 16 and 18 are transposed, thereby reversing the direction of 50 current flow in the calling lines. This reversal of current, as is well known in the telephone art, is for the purpose of operating the calling subscriber's meter or to operate his coin-collect 55 mechanism as the case may be.

The connection now having been completed, the calling and called subscriber may converse with each other as desired. After the conversation is completed both subscribers hang up their 60 receivers. Since the connector switch C is of the well known last-party-release-type switch, the connection is not released until both subscribers have replaced their receivers. If the calling subscriber hangs up first, the loop circuit of line relay 203 is open. The line relay 203 restores to normal and upon falling back opens the circuit of the release relay 204. Release relay 204 subsequently falls back and at the resting contact of 65 armature 218 prepares a circuit for the release

magnet 213. This circuit however is not completed until the back bridge relay 201 restores to normal and closes its lower armature and resting contact. The removal of ground at armatures 216 and 217 has no effect at this time because 5 relay 201 is still operated. When the called subscriber hangs up his receiver the loop circuit for back bridge relay 201 is open and the relay is accordingly restored to normal. Relay 201 removes ground from the release conductor 10 17 at armature 261 thereby causing the selector switch S and the calling subscriber's line switch LS to be released in the well known manner. Relay 201 opens the locking circuit for the ring-cut-off relay 206 and the switching relay 210 at 15 armature 262 and they accordingly restore to normal. At the lower armature of back bridge relay 201, the following circuit is completed for the release magnet 213: ground, armature 219 and its resting contact, armature 218 and its resting 20 contact, lower armature and resting contact of the back bridge relay 201, contacts 245 of the operated off-normal springs ON, winding of release magnet 213, to battery. The operation of 25 release magnet 213 causes the shaft of the connector to restore to normal and it accordingly opens the circuit to the release magnet 213 by opening contacts 245 of the off normal springs ON. All the apparatus used in establishing the 30 above described connection is now in its normal position and may be used for extending other calls. It may be well to mention at this time however, that if the called subscriber replaces his receiver first the back bridge relay 201 restores to normal and again transposes the connection 35 between conductor 16 and 18 and the battery and ground through the windings of the line relay 203, and at armatures 261 and 262 opens a point in the circuit which is now maintained from armatures 216 and 217 on the release 40 relay 206. At its lower armature and resting contact, back bridge relay 201 also prepares a point in the circuit for operating the release magnet 213. This circuit is not completed because the 45 line relay 203 has not been deenergized. When the calling subscriber hangs up his receiver, the line relay 203 and release relay 204 restores to normal and the circuit for the release magnet 213 is now completed. The holding ground potential is removed from release trunk conductor 17 at 50 armature 216 and the locking circuit for ring-cut-off relay 206 and switching relay 210 is opened at armature 217 and the relays restore to normal. From the foregoing description of the release of the connector switch C, it will be understood that 55 the connection will not be restored to normal until the last party hangs up his receiver.

The foregoing description was for the purpose of describing the operation of the connector switch C when local subscribers of the telephone exchange establish connections. A detailed description will now be given of the operation that takes place when the toll operator at the manual switchboard has received a toll call, from a distant city, for a subscriber in the automatic exchange. It will be assumed for this purpose, that the subscriber at substation A is the subscriber wanted to complete the toll call.

The toll operator, upon receiving a call from a distant manual exchange, answers this call by inserting the answering end of the plug of her cord circuit into the answering jack and receives the number of the wanted subscriber in the automatic exchange from the calling manual subscriber. It will be assumed that the subscriber desired is the 75

subscriber at substation A which is accessible to the operator over the trunk terminating in jack J. The operator, upon observing the idle condition of the busy visual 1, seizes the associated trunk by 5 inserting the plug P into jack J, and by then operating her key K. Upon insertion of the plug P into jack J, busy visual signal 1 is operated from ground supplied by spring 2 and its grounded working contact. The operation of the busy 10 visual signal indicates to other operators, at whose position this trunk is multiplied, that the trunk is taken into use. Responsive to the operation of key K, a circuit is closed for sleeve relay 3 of the cord, by way of spring 20 and the sleeve 15 of plug P, which has been grounded by spring 2 of jack J. Relay 3, upon operating, at armature 5 completes a locking circuit for itself independent of the spring 4 controlled by key K and at armature 6 prepares a circuit for polarized 20 relay 7.

The operation of key K also connects the calling device CD to the tip and ring conductor of cord O. This completes a loop circuit by way of plug P, jack J, and conductors 8 and 9 to the 25 line relay of the line switch LS, which is similar to line switch LS-1 shown in Fig. 2. Responsive to the operation of the line relay in the line switch LS, the rotary magnet is operated in the well-known manner and seizes a trunk line extending to an idle selector switch, such as selector switch S. The selector S is one of a plurality of such selectors which are accessible to the toll operator by way of line switch LS. The selector S is prepared for operation in response to its seizure 30 over the loop circuit, which now includes wipers 19 and 21 of the line switch LS, and ground is returned over the test conductor and test wiper 20 of the line switch to maintain the line switch in its operated position. The operator now operates 35 her calling device CD in accordance with the first digit of the wanted subscriber's number, thereby controlling the selector to raise its wipers 13-15, inclusive, to the group of bank contacts in which the trunk to the desired hundred group of connectors is terminated. The vertical magnet of 40 the selector switch S is then automatically operated in the well known manner to rotate the wipers 13-15, inclusive, to find an idle trunk line extending to a connector switch. It will be assumed that the wipers 13-15, inclusive, seize the 45 trunk conductors 16-18, inclusive, extending to an idle connector switch C. The selector switch S switches through in the well known manner and extends the loop circuit over wipers 13 and 15, conductor 16 and 18, normally closed contact 50 controlled by armatures 215 and 214, lower and upper windings of three-pole electro-polar relay 202, lower and upper windings of line relay 203, to battery and ground respectively.

55 The operation of the connector switch C under control of the toll operator at the manual switchboard, is exactly the same as has previously been described in connection with a local call. It will therefore be assumed, that the operator has dialed 60 the second digit, and has accordingly operated the vertical magnet 211 of the connector to raise the wipers 223-225, inclusive, of the switch to the level in which the wanted subscriber's line is terminated, and that in response to the last digit 65 of the wanted subscriber's number the rotary magnet 212 has rotated the wipers 223-225, inclusive, into engagement with the set of bank contacts associated with substation A. If the wanted subscriber's line is idle, the connector operates in 70 the well known manner, which has previously been

described in detail, seizes the called line, transmits the ringing current, and when the wanted subscriber answers, the connection is completed between the operator at the manual switchboard and the wanted subscriber at substation A. 5

In order to describe the toll offering feature of the present invention, it will be assumed for the present that the subscriber at substation A is busy when the wipers of the connector are positioned into engagement with his line. Therefore, the cut-off relay 233 of line switch LS-1, which is individual to the wanted subscriber's line, is operated and test conductor 231 is grounded by the connector and selector switch over which his connection is extended by way of wiper 247, and 10 armature 236 and its front contact. The ground returned over this path also extends by way of the winding of relay 233, self-interrupting contacts of the operating magnet 249, and winding of the operating magnet 249, to battery to maintain 15 relay 233 operated.

After the last impulse of the last digit has been transmitted to the rotary magnet and relay 209, as has been previously described, slow to release relay 209 remains operated for a short period of 25 time. The ground potential encountered by the test wipers 224 on conductor 231 completes a circuit for the busy test relay 208 over the following path: wiper 224, armature 229 and its front contact, armature 228 and its resting contact, winding of busy test relay 208, to battery. At armature 239 and its front contact, relay 208 prepares a locking circuit for itself from ground at armature 216. This circuit is completed subsequently at the normally closed contact controlled by armature 229 and its front contact, when relay 209 falls back. 30

Immediately after the operator has transmitted the last digit of the wanted subscriber's number, she restores her key K to normal. This 40 extends the loop circuit to the right-hand winding of the repeat coil R, in series with the polarized relay 7 and the armature 6 of the operated sleeve relay 3. The loop circuit for the line relay 203 of the connector circuit may now be 45 traced over the following path: ground, upper winding of line relay 203, upper or operating winding of the three-pole electro-polar relay 202, normally closed contacts controlled by armature 214, conductor 18, wiper 15 of the selector S, 50 wiper 21 of the line switch LS, conductor 9, jack J, plug P, normally closed contacts of the lower spring combination of the key K, lower right-hand winding of the repeating coil R, armature 6, both windings of polarized relay 7, upper right-hand winding of the repeating coil R, normally 55 closed contacts of the upper spring combination of the key K, plug P, jack J, conductor 8, wiper 19, of the line switch LS, wiper 13 of the selector S, conductor 16, normally closed contacts controlled by armature 215, lower or polarizing winding of the electro-polar relay 202, lower winding of line relay 203, to battery. The line relay 203 remains operated when the key K is restored to normal, however, the polarized relay 7, which is now included in the loop circuit of line relay 203, operates and thereby lights the supervisory lamp L at the operator's position. 60

Referring again to the operation of the busy test relay 208, it will be noted that at armature 70 242 and its front contact, the busy tone from the busy machine is connected by way of armature 261 and its resting contact to the trunk conductor 18. When the toll operator hears the busy tone she knows that the wanted subscriber 75

is already engaged in a telephone connection. The operator can either withdraw her plug P from jack J to release the connection or she can control the connector to cut in on the busy line and offer the toll call to the busy subscriber.

5 In case the operator wishes to offer the toll call to the wanted subscriber, she momentarily depresses the toll offering key K2 thereby connecting positive booster battery to the loop circuit for the line relay 203. When positive booster battery is connected to the loop circuit, two separate circuits may be traced. One circuit is as follows: from positive booster battery (negative terminal grounded), resistance 27, key K2, plug 10 P, jack J, conductor 9, wiper 21 of the line switch LS, wiper 15 of the selector S, conductor 18, armature 214 and its normally closed contacts, operating winding of the three-pole electro-polar relay 202, upper winding of line relay 203, to ground. This circuit reverses the direction of 15 normal current flow in the operating winding of relay 202 and the upper winding of line relay 203. The other circuit, closed simultaneously with the above traced circuit is as follows: from positive booster battery, resistance 27, key K2, lower key 20 K, lower right hand winding of repeating coil R, armature 6, windings of polarized relay 7, upper right hand winding of repeating coil R, upper key K, plug P, jack J, conductor 8, wiper 19 of 25 line switch LS, wiper 13 of the selector S, conductor 16, armature 215 and its normally closed contacts, lower or polarizing winding of relay 202, lower winding of line relay 203, to negative exchange battery. In this circuit the normal flow of current is increased considerably due 30 to the fact that the two batteries are in series. Considering these two circuits together, it will be noted that by reversing the direction of current flow in the operating winding of relay 202, the current flow through the two windings of the 35 relay assist each other and the relay operates. Although the direction of current flow in the upper winding of relay 203 has been reversed, the relay does not fall back because the current flow 40 through its lower winding has been increased by the application of booster battery in series with the regular exchange battery. Therefore line 45 relays 203 of the connector and polarized relay 7 of the operator's cord O remain energized and relay 202 is operated. In response to the 50 momentary operation of relay 202 a circuit is completed for the toll offering relay 207 over the following path: ground at the lower armature of relay 209, armature 241, armature 244, winding 55 of toll offering relay 207, to battery. Relay 207 operates and at armature 262, completes a locking circuit for itself independent of the circuit including armature 244. When the toll offering key K2 restores to normal, the normal loop circuit including the line relay 203, electro-polar relay 202, and the polarized relay 7 in the operator's cord circuit, is again completed. The line 60 relay 203 and the polarized relay 7 remain operated as before, and the three-pole electro-polar relay 202 restores to normal. Referring again to the operation of the toll offering relay 207, it will be noted that at armature 261 the busy tone transmitted to the operator is disconnected from the lower trunk conductor. At armature 243, 65 relay 207 transfers the holding circuit for the busy test relay 208 from the grounded release conductor 17 to the grounded test wiper 224. Due to its slow-to-release characteristics, busy test relay 208 remains energized while this transfer 70 is made. At armature 259 and 260, toll offering 75

relay 207 disconnects the back bridge relay 201 from the talking conductors of the trunk and at the front contacts of these armatures connects the talking conductors of the trunk through to the busy subscriber's line.

5 It will be noted from the above description that even if the subscriber at substation A is busy in the conversation with another local subscriber and the line is marked busy, the operator, by means of the toll offering key K2, can control the connector switch C to cut in on the busy line.

10 The toll operator may now inform the called subscriber that he is desired for a toll call. If the subscriber at substation A does not wish to take the toll call at the present time, the operator removes her plug P from the jack J and the entire connection is released in the well known manner. In the event that the subscriber A wishes to take the toll call, he informs the subscriber with whom he has been conversing and they both hang up their receivers. When the 15 subscribers engaged in the local connection hang up their receivers, the switches used in establishing the connection, restore to normal and the ground potential is removed from the test conductor 231.

20 When this occurs, the busy relay 208, which was held in its energized position from the grounded conductor 231, restores to normal. In response to the restoration of relay 208, the following operations take place. The locking circuit 25 for the toll offering relay 207 is opened at armature 241 and the relay accordingly restores to normal. At armature 239, the original locking circuit for the busy test relay 208 is opened, and at armature 240 the circuit for the lower winding 30 of the switching relay 210 is again closed. When the toll offering relay 207 restores to normal the windings of the back bridge relay 201 are again connected to the talking conductors of the trunk at armatures 259 and 260 and their respective 35 resting contacts. The circuit for energizing the switch-through relay 210 is completed from ground at armature 216, armature 240, lower winding of switching relay 210, armature 229 and its resting contacts, wiper 224, conductor 231, winding of the cut-off relay 233, self-interrupting 40 contacts of the operating magnet 249, winding of the operating magnet 249, to battery. The operating magnet 249 does not respond over this circuit. However, the cut-off relay 233 and the 45 switching relay 210 both energize. As has been described hereinbefore, the line switch is of the well known interlocking mechanism type and it will suffice to state that the cut-off relay clears the called line of attachments. Switching relay 50 210, upon operating, completes a locking circuit by way of its upper winding and armature 250 to ground at armature 217, and at armature 254 places an additional holding ground for the cut-off relay 233, which is independent of the circuit just traced in series of the lower winding of 55 switching relay 210. The lower winding of the switching relay 210 is now shunted by ground at armature 216 and at armature 254. Relay 210 opens a point in the circuit for the rotary magnet 60 212 at armature 228, and at armature 252 prepares the ring-back tone circuit to indicate to the operator that the ringing has been started. At armature 251 and 253 and their respective front 65 contacts, switching relay 210 connects interrupted generator to the called line. The ringing current from the generator INT. GEN. is intermittently projected over the called line to operate the ringer at substation A. The ringing circuit is the same as has been described as hereinbefore, 70 75

and it should be understood that when the ringing current is transmitted, the ring-back tone circuit which is completed at armature 252 is heard by the operator at the toll switchboard 5 and indicates to her that the signalling has begun. When the called party answers the call by removing his receiver from the switchhook, the ring-cut-off 206 operates and locks itself at armature 256, to ground at armature 217. At 10 armatures 255 and 257, relay 206 opens the ringing circuit and at the front contacts of these armatures connects the talking conductors of the called line straight through to the calling line thereby connecting the windings of the back 15 bridge relay 201 to the called line. The back bridge relay 201 energizes over the loop circuit including the called line and at armatures 215 and 214 and their respective front contacts reverses the direction of current flow over trunk conductors 16 20 and 18 to the polarized relay in the operator's cord circuit O. Due to the reversal in the direction of current flow through the windings of the polarized relay 7, the relay restores to normal and causes the lamp L to be extinguished, thereby 25 notifying the operator that the called subscriber has answered. Transmission battery is supplied to the calling line or operator's trunk line by line relay 203 and is supplied to the called line by back bridge relay 201. The operator at the toll 30 board now restores her listening key to disconnect her head set from the trunk and the calling subscriber in the distant manual exchange may now converse with the automatic telephone subscriber at substation A. Transmission battery is supplied to the calling manual subscriber from 35 the windings of relay 23. After the conversation has been completed, both subscribers hang up their receivers.

When the distant manual exchange subscriber hangs up his receiver, the supervisory lamp L2 40 is lighted at the toll board and indicates to the operator that the calling subscriber has released the connection. The operator removes the answering end of the cord circuit O from the 45 answering jack (not shown) thereby releasing the distant exchange trunk for other calls. When the subscriber at substation A hangs up his receiver, the back bridge relay 201 is restored to normal and again reverses the direction of current flow through the polarized relay 7 at the 50 operator's cord circuit O. The direction of current flow through the relay is in the proper direction and the relay energizes, lighting the supervisory lamp L, thereby indicating to the operator that the called subscriber has released the connection. The operator now removes the 55 plug P, of the circuit O, from the jack J and sleeve relay 3 and polarized relay 7 both restore to normal. When the plug P is removed from the jack J, ground is removed from spring 2 of the jack and the busy visual 1 and all other busy visuals operated over the multiplied conductor are restored to normal. The loop circuit, over which line relay 203 of the connector C was 60 operated, is opened by the removal of the plug P and the connector switch restores to normal. Ground is subsequently removed from the release trunk conductor 17 and results in the restoration of the selector switch S and the line switch LS. 65 The switches are now in a position to be seized for another call.

The operation of the connector has been described when it is used as a regular local connector by regular subscribers in the automatic system, and a description has also been given of the

operation of the connector when it is used as a toll offering connector under control of the toll operator. The connector functions in the same manner in both connections with the exception that when the operator extends the call to a busy line, she may, at her discretion, cut in on the busy subscriber's line and offer the toll call to the subscriber thereon or she can release the connection. In order for her to offer the connection to the busy subscriber, she must operate 10 her toll offering key K2 to connect positive booster battery to the trunk conductors. The three-pole electro-polar relay will then respond to initiate the operation required for the connector to cut in on the busy line and also to prevent the ringing current from being connected thereto. If a local subscriber should attempt to operate the connector to cut in on a busy line by grounding either of the line conductors, the three-pole electro-polar relay 202 will not respond because if 15 one of the conductors is grounded, the circuit for the operating winding of the electro-polar relay is short circuited and if ground is applied to the other trunk conductor, a circuit will be completed for the polarizing winding but no 20 amount of current flow through the polarizing winding will energize the electro-polar relay when the operating winding has no current flow. 25

A description will now be given of the operation of the equipment when the operator at the toll board receives a toll call from the distant manual exchange and desires to extend the call to an automatic subscriber in a distant automatic exchange.

It will be assumed that the operator at the toll switchboard has received such a call and has inserted the plug P, of the cord circuit O, into jack J and that the line switch LS has seized an idle selector switch such as selector switch S. Furthermore, it will be assumed that the first digit of the wanted subscriber's number has been dialled and that the selector S, under control of the vertical and rotary magnets, has raised the wipers 13-15, inclusive, to the proper level and that the wipers have been rotated over the bank contacts and have engaged an idle trunk line extending to an outgoing trunk repeater, such as outgoing trunk repeater OTR. Therefore, the trunk comprising conductors 24-26, inclusive, extending to the outgoing trunk repeater OTR, is 50 the trunk engaged by the selector switch S.

In response to the seizure of the outgoing trunk repeater OTR, by the selector S, the line relay 304 is operated over the following path: ground, upper winding of line relay 304, upper or operating winding of the three-pole electro-polar relay 303, upper left-hand winding of repeater coil R1, normally closed contacts controlled by armature 309, conductor 26, wiper 15 of the selector switch S, wiper 21 of the line switch LS, conductor 9, 60 jack J, plug P, operated contacts of the lower springs of key K, calling device CD, operated contacts of the upper springs of key K, plug P, jack J, conductor 8, wiper 19 of the line switch LS, wiper 13 of the selector S, conductor 24, normally closed contacts controlled by armature 306, lower left-hand winding of repeater coil R1, bottom or polarizing winding of relay 304, to battery. Relay 304 completes an obvious circuit for the slow-to-release relay 305 which energizes and at its upper 65 armature places a ground potential on the release conductor 25 to maintain the selector S and line switch LS in an operated position, and at the same time completes a circuit for the right-hand winding of the shunt-field 302. Relay 302 is not 70 75

operatively energized at this time, owing to the fact that the flux that is generated in the right-hand core is shunted away from the armature and heelpiece by the left-hand core. It will be noted that when relay 304 energized that a circuit was closed at armature 310 to complete a loop circuit by way of the trunk conductors 30 and 31 to the automatic switches in the distant automatic exchange. When this loop circuit is closed the switches in the distant automatic office are seized in the usual manner and are prepared to receive the impulses transmitted by the operator at the toll board. The line relay 304, of the outgoing trunk repeater OTR, repeats the impulses over the trunk line by momentarily opening and closing the loop circuit at armature 310 in accordance with the impulses transmitted from the operator's calling device CD. Release relay 305, due to its slow release characteristics, remains energized during the impulse series. The loop circuit including conductors 30 and 31, which is closed by armature 310, also includes the right-hand windings of the repeating coil R1 in series with the left-hand winding of the shunt field relay 302. The shunt field relay 302, however, is not energized at this time, because the flux generated in the left-hand winding coincides in direction with the flux normally shunted from the armature by the core associated with said winding. Each core now acts as a magnetic short circuit for the flux generated in the other core. The toll operator dials the number of the wanted subscriber in the distant automatic exchange and the line relay 304 of the outgoing trunk repeater responds, thereby repeating impulses, by way of armature 310, over the trunk conductors 30 and 31. The operator then restores her key K to normal to disconnect the calling device CD from the line. The switches in the distant automatic office are controlled by the impulses transmitted over the trunk line and extend the connection to the wanted subscriber's line.

It will be assumed that the final digits of the wanted subscriber's number operates a connector switch, similar to the connector switch C shown in Fig. 2, and that the line of the wanted subscriber is similar to the line of substation A in Fig. 2. It will therefore be understood from the previous description of the connector switch C, that if the wanted line is idle the switching relay of the connector is operated, ringing current is transmitted over the wanted subscriber's line, and the wanted subscriber is signalled in the usual manner.

It will be assumed, for the purpose of this description, that the wanted subscriber's line is busy when the connection is extended to his line and that the busy tone is received, in the usual manner, by the operator at the toll board. Since the connectors in the distant automatic office are of the toll offering type, the operator can, by operating her toll offering key K2, control the connector at the distant office to cut in on the busy subscriber's line so that the operator may offer the toll call to the subscriber connected thereto.

Therefore, it will be assumed that when the operator at the toll board receives the busy tone indicative of the fact that the called subscriber is engaged in a conversation, that the operator desires to offer the call to the busy subscriber.

When the operator momentarily depresses her toll offering key K2, positive booster battery is applied to the tip and ring conductors of the plug 75 P, jack J, conductors 8 and 9 extending to the

line switch LS, wipers 19 and 20, wipers 13 and 15 of the selector S, to conductors 24 and 26, respectively, extending to the outgoing trunk repeater OTR. It will be noted that the booster battery extending over the tip conductor of the 5 operator's cord circuit is in series with the polarized relay 7 in the operator's cord. Referring now to Fig. 3, it will be noted that the booster battery applied to conductor 26 is extended by way of the normally closed contacts controlled 10 by armature 309, upper winding of the repeating coil R1, upper or operating winding of the three-pole electro-polar relay 303, upper winding of line relay 304 to ground. The booster battery applied to conductor 24 is extended by way of the 15 normally closed contacts controlled by armature 306, lower left-hand winding of the repeating coil R1, lower or polarizing winding of the three-pole electro-polar relay 303, lower winding of line relay 304, to battery. Therefore, the normal current flow in the circuit for the lower windings of relays 303 and 304 is increased considerably when booster battery is applied to conductor 24 due to the fact that the two batteries are in series. The booster battery applied to conductor 26 reverses 20 the direction of current flow in the upper or operating winding of relay 303 and the upper winding of line relay 304. Considering these two circuits together, it will be noted that by reversing the direction of current flow in the operating 25 winding of relay 302, the current flow through the two windings of the relay assist each other and the relay operates. Although the direction of current flow in the upper winding of line relay 304 has been reversed, the relay does not fall 30 back because the current flow through its lower winding has been increased by the application of booster battery in series with the regular exchange battery. Therefore, line relay 304 of the 35 outgoing trunk repeater OTR, and polarized relay 40 7 of the operator's cord O remain energized and three-pole electro-polar relay 303, of the outgoing trunk repeater OTR, operates. In response to the momentary operation of the electro-polar relay 303, booster battery is applied, at the upper 45 and lower armatures, to the trunk conductors 30 and 31 extending to the distant exchange.

As has been mentioned, hereinbefore, the connector switch at the distant automatic exchange is the same as the connector switch C shown in 50 Fig. 2. Therefore, it will be understood, that the operation of three-pole electro-polar relay of the connector of the distant exchange initiates the operation for controlling the switch to cut in on the busy subscriber's line. The toll offering 55 key K2 in the operator's cord circuit O, which is only momentarily operated, disconnects the booster battery potential from the trunk conductors 24 and 26, extending to the outgoing trunk repeater OTR, and the three-pole electro-polar 60 relay 303 restores to normal and in doing so removes the booster battery potential from the trunk conductors 30 and 31 extending to the polar relay of the connector switch in the distant 65 exchange. Since the connector switch of the distant exchange has cut in on the busy line, the busy tone is removed from the trunk conductors and the operator may offer the toll call to the busy subscriber.

If the subscriber does not desire to take the toll call at the present time, the operator merely pulls down the connection by removing the plug P from the jack J. However, if the subscriber desires to take the toll call, he advises the sub- 75

scriber with whom he is engaged in conversation, and they both hang up their receivers.

As soon as the subscribers hang up their receivers, the ring-cut-off relay, of the distant exchange connector, connects the ringing current to the wanted subscriber's line and he is signalled in the same manner as has been hereinbefore described.

Responsive to the called subscriber answering, 10 the back bridge relay of the connector operates and in doing so reverses the direction of current flow over conductors 30 and 31. The reversal in the direction of current flow in conductors 30 and 31 obviously reverses the direction of current flow 15 in the left-hand winding of the shunt field relay 302. Heretofore the magnet flux set up by left-hand winding of relay 302 has been in such a direction as to coincide with that set up by the right-hand winding of said relay and accordingly 20 the flux was short-circuited, so to speak, as none of it was forced to flow out through the heel piece and armature of the relay but rather flowed through the two cores and associated yoke in series. Due to the reversal of current in the left-hand winding, however, the flux produced thereby 25 opposes that produced by the right-hand winding, thus forcing it to pass out through the heel piece and armature and return through the two cores in parallel. The armature of the relay is 30 now attracted and closes a circuit for the reversing relay 301. At armatures 306 and 309 and their associated front contacts, reversing relay 301 reverses the direction of current flow in the loop circuit of the operator's cord circuit O. Due to 35 this reversal of current, the polarized relay 7 of the operator's cord circuit O falls back, thereby extinguishing the supervisory lamp L. This notifies the operator that the called subscriber has answered. Reversing relay 301 of the outgoing 40 trunk repeater, at armatures 307 and 308, places a short circuit around the upper and lower winding of the three-pole electro-polar relay 303 to remove their impedance from the transmission circuit.

45 The connection is now completed between the subscriber at the distant manual exchange and the wanted subscriber at the distant automatic exchange. When the conversation is completed and the subscribers hang up their receivers, the operator at the manual switchboard receives the usual disconnect signal by the lighting of lamp L2 when the distant manual subscriber hangs up his receiver and by the lighting of lamp L when the distant automatic exchange subscriber 50 hangs up his receiver. Briefly, when the distant automatic exchange subscriber hangs up his receiver, the connector again reverses the direction of current flow in the trunk conductors 30 and 31 and the shunt field relay 302 restores to normal. The shunt-field relay 302 restores to normal because the flux generated in the left-hand winding now coincides in direction with the flux generated in the right-hand winding of the relay. Each core now acts as a magnet short-circuit for 55 the flux generated in the other. At its lower armature, shunt field relay 302 opens the circuit for the reversing relay 301 which restores to normal and its armatures 306 and 309 again reverse the direction of current flow in the operator's cord circuit O. The electro-polarized relay 7 thereat operates and lights the lamp L to indicate to the operator that the distant automatic exchange subscriber has replaced his receiver on the switchhook. The operator now 60 removes the plug P from the jack J thereby

opening the loop circuit for maintaining line relay 304 of the outgoing trunk repeater energized. Line relay 304 falls back and at armature 310 opens the loop circuit for holding line relay of the connector at the distant exchange in its operated position. The line relay of the connector at the distant exchange falls back, opens the circuit for the release relay which also falls back and completes the circuit for operating the release magnet and at the same time removes 10 ground from the release trunk to release all other switches used in establishing the connection. Responsive to the operation of the release magnet the switch restores to normal. Due to the falling back of line relay 304 of the outgoing 15 trunk repeater OTR, release relay 305 falls back and at its upper armature removes the holding ground from relay 302 and the release trunk conductor 25. The selector and line switch used in completing the connection both restore to 20 normal in the well known manner.

The operator now removes the plug P from the jack J and the circuit for the busy visual 1, and all busy visuals multiplied thereto, is opened at spring 2 of jack J. In the operator's cord, 25 the circuit for the sleeve relay 3 is accordingly opened when the plug P is removed from the jack J and at armature 6 the circuit for the polarized relay 7 is opened. Polarized relay 7 restores to normal and the lamp L is extinguished. The 30 cord circuit is now available for completing other connections.

It should be clearly understood, from the foregoing description, that the invention covers new and improved circuits for completing toll offering connections in an economical and efficient manner, and that the local telephone subscribers cannot control the circuits to cut in on busy lines. 35

What is claimed is:

1. In a telephone system, subscribers' lines, 40 means for making any of said lines busy, an operator's switchboard, automatic switches, operator controlled means for operating said switches to extend a connection to one of said busy lines, a booster battery, operator controlled means for 45 connecting said booster battery to said connection, and means at one of the switches responsive to the connection of said booster battery for completing a talking connection with said busy line.

2. In a telephone system, a subscriber's line, 50 means for making said line busy, automatic switches, an operator's position and means thereat for operating said switches to extend a connection to said busy line, means at said position for momentarily applying a battery potential augmenting the exchange battery potential to the talking conductors of said connection to operate one of said switches to establish a talking connection with said busy line, and means responsive to the establishment of said talking connection for preparing said one switch to signal the subscriber on said line when said line becomes idle. 55

3. In a telephone system, calling lines of two 60 classes, called lines, automatic switches, means for operating said switches to establish a connection from a calling line of either class to a called line, means for preventing one of said switches from completing a talking connection 65 when a connection is extended to a busy called line, means controlled by a calling subscriber of one class when connected to a busy called line for connecting an abnormal direct current potential to the connection, and means responsive 70 to the connection, and means responsive 75

- to said potential for controlling said one switch to establish a talking connection between the calling line of said one class and said busy called line.
5. In a telephone system, a called station, an operator's position, automatic switches including a connector switch, an exchange battery, means at said operator's position included in a circuit with said exchange battery for operating said switches and said connector to establish a connection with said called line, a booster battery, means at said position for connecting said booster battery to said circuit, and means responsive only to the application of said booster battery for operating said connector to extend a talking connection to said called line when it is busy.
10. In a telephone system, an operator's switchboard, a trunk line, a repeater for extending connections over said trunk line to a distant automatic exchange, switches at said distant exchange for extending connections to busy or idle subscribers' lines, means at said operator's switchboard for establishing a connection via said repeater and trunk line to said automatic exchange switches, means for operating the switches at said exchange to select a wanted subscriber's line, means at said operator's switchboard for controlling said repeater to send current of an increased potential over the conductors of said trunk line, and means at one of said switches responsive to said current of an increased potential for enabling said operator to establish said connection when said line is busy.
15. In a telephone system, calling stations of two classes, an automatic switch common to both classes, said switch having access to called stations, means at said calling stations for operating said switch to establish a connection with a called line, means for preventing the completion of a connection with a busy called line when a station of one class extends said connection, a booster battery, means at the station of the other class for momentarily applying said booster battery to the talking conductors when a busy line is encountered, and means in said switch responsive only to the application of said battery for completing a talking connection with a busy line.
20. In a telephone system, a first class calling station, a second class calling station, automatic switches common to both classes, a called station, means at said calling stations for operating said switches to extend a connection to a called station over two paths, one of said paths automatically predetermined to establish a talking connection between a calling and a called station when said called station is idle, the other of said paths selectable only by said first class calling station to extend a talking connection to said called station during the time said called station is busy, means at said first class calling station for momentarily increasing the current flow in one of the talking conductors and simultaneously reversing it in the other talking conductor of said connection, and means in one of said switches responsive only to said increase and reversal of current for selecting said other path.
25. In a telephone system, a calling station, a busy called station, an automatic switch, means for operating said switch to extend a connection from said calling station to said busy called station, means automatically operable responsive to said connection for notifying said calling sta-
- tion of the busy condition of said called station, a relay in said switch for transmitting ringing current to signal a called station only when it is idle, a source of direct current at said calling station, means for connecting said current to the line conductors of said calling station, means in said switch operated in response to said current for controlling said switch to complete a temporary talking connection between said calling station and said busy called station, and means operated responsive to said busy called station becoming an idle called station for disconnecting said temporary talking connection and for operating said relay.
30. In a telephone system, a calling station, a called station, an automatic switch operated from said calling station to extend a call to said called station, a switching relay in said switch for closing a circuit to apply ringing current to the line of said called station, means for preventing the operation of said switching relay when said called station is busy, a toll offering relay for extending a talking connection to a busy line, means for operating said toll offering relay controlled by the momentary application of battery potential to the talking conductors at said calling station, and means responsive when said busy line becomes idle for automatically disconnecting said toll offering relay and for operating said switching relay.
35. In an automatic telephone system, a busy line, switches including a connector, means for operating said switches to extend a connection to said connector, means for operating said connector to engage said busy line, means for sending an impulse of current of an increased potential over said connection to said connector, means in said connector responsive only to said current of increased potential for completing a talking connection for a third party with said busy line.
40. In a telephone system, a first and second automatic exchange, a trunk line from said first exchange to said second exchange, an operator's position, a busy called station at said second exchange, automatic switches at both of said exchanges, an outgoing trunk repeater at said first exchange connected to said trunk line, means at said operator's position for extending a connection to said automatic switches in said first exchange and for transmitting impulses to said switches to extend said connection to said repeater and trunk line to select switches in said second exchange, means in said repeater for repeating subsequent impulses from said operator's position over said trunk line to control said switches at said second exchange to extend said connection to said busy called station, means at said operator's position for further controlling the operation of said repeater to transmit a pulse of current of positive potential over said trunk line, and means at one of said second exchange switches responsive only to said pulse of current of a positive potential for controlling said one switch to complete a talking connection with said busy called station.
45. In a telephone system, a manual exchange, an automatic exchange and switches thereat, a trunk line extending from said manual exchange to said automatic exchange, means responsive to the seizure of said trunk line by the operator at said manual exchange for preparing said switches in said automatic exchange for operation, means for transmitting impulses over said trunk line to operate said switches into engage-

- ment with a desired line, means for signalling the operator at said manual exchange when the desired line is busy, a key at said manual exchange for connecting a battery potential to said trunk line, means at said automatic exchange responsive only to a momentary application of said battery potential over said trunk line for establishing a talking connection with the busy called line. 5
13. In a telephone system, subscribers' lines, 10 means for making any of said lines busy, an operator's position, automatic switches, means at said operator's position for operating said switches to extend a connection to one of said busy lines, a normal current flow in said connection, a booster battery, means at said operator's position for connecting said booster battery to said connection, and means at one of said switches non-responsive to said normal current flow and responsive to the current flow from said booster battery for completing a talking connection between said operator's position and said busy line. 15
14. In a telephone system, a calling station, a busy called station, an automatic switch, a dialling circuit from said calling station to said switch, means in said switch controlled over said circuit for extending a connection from said calling station to said busy called station, a booster battery at said calling station, means for connecting said booster battery to said dialling circuit, 20 means in said circuit responsive to the current from said booster battery for controlling said switch to complete a talking connection between said calling station and said busy called station. 25
15. In a relay controller, a line relay, a three-pole electro-polar relay, a battery having its positive terminal grounded, an energizing circuit for said line relay including the negative terminal of said battery, one winding of said line relay, polarizing winding of said polar relay, the operating 30 winding of said polar relay, the other winding of said line relay and the positive terminal of said battery, a booster battery having its negative terminal grounded, means for connecting said booster battery to said energizing circuit in such a manner that the current flow in the operating winding of said polar relay is reversed, said polar relay operated responsive to the reversal in the direction of current flow in its operating winding only. 35
16. In a relay controller, a line relay, a three-pole electro-polar relay, a battery having its positive terminal grounded, an energizing circuit for said line relay including the negative terminal of said battery, one winding of said line relay, polarizing winding of said polar relay, the operating winding of said polar relay, the other winding of said line relay and the positive terminal of said battery, a booster battery having its negative terminal grounded, means for connecting 40 said booster battery to said energizing circuit in such a manner that the current flow in the operating winding of said polar relay and one winding of said line relay is reversed and the current flow in the polarizing winding of said polar relay and one winding of said line relay is increased, said polar relay operated responsive to the reversal of said current flow and said line relay maintained energized responsive to the increased current flow in one of its windings. 45
17. In a telephone system, calling and called lines, means including an automatic switch controlled from a calling subscriber for operating 50
- said switch to extend a connection to a called line, means for preventing the completion of said connection when the called line is busy, a loop circuit over which said switch was controlled, a relay in said circuit normally inoperative during the extension of said connection, an auxiliary battery, and means for connecting said battery to said loop circuit to operate said relay to complete said connection. 55
18. In a telephone system, calling and called lines, means including an automatic switch controlled from a calling subscriber for operating said switch to extend a connection to a called line, means for preventing the completion of said connection when the called line is busy, a loop circuit over which said switch was controlled, a two winding relay in said circuit normally inoperative during the extension of said connection, an auxiliary battery, means for connecting said battery to said loop circuit in such a manner that the current flow in one winding of said relay is reversed and the current flow in the other winding is increased, said relay operated responsive to said reversal of current in one winding to complete said connection. 60
19. In a telephone system, an automatic switch having access to busy and idle subscribers' lines, means in said switch when associated with a busy subscriber's line for completing a connection to said line, means for reversing the direction of current flow in one of the conductors incoming to said switch and simultaneously increasing the current in another conductor incoming to said switch, said first means responsive only to said reversal and increase of current in said conductors. 65
20. In a telephone system, a calling station, a busy called station, an automatic switch, means for causing said switch to extend a connection from the calling station to the busy called station, a source of special direct current potential at the calling station, means at said calling station for connecting said source to the talking conductors of the connection, a relay in said switch responsive to the current from said source for causing the completion, in said switch, of the connection to the busy station. 70
21. In a telephone system, a repeater, lines incoming to said repeater conductively isolated from lines outgoing from said repeater, a means for reversing the direction of current flow in one of the incoming conductors to said repeater and simultaneously increasing the current in another conductor incoming to said repeater, means, responsive only to said reversal and increase of current in said incoming conductors, for reversing the direction of current flow in one of the conductors outgoing from said repeater and increasing the current in another conductor outgoing from said repeater. 75
22. In a relay controller, a series circuit including the windings of a line relay, another relay and an exchange battery of ordinary potential, means for producing an extraordinary potential at a point in said circuit thereby reversing, in each of said relays, the direction of current flow in at least one but not all of said windings, said means effective only to operate said second relay, said second relay operative responsive only to said means. 80
